United States Patent Office

Des. 183,314
Patented Aug. 5, 1958

183,314

PULL

Wallace T. Johnson, Burbank, Calif., assignor to
Amerock Corporation, Rockford, Ill., a corporation
of Illinois

Application May 16, 1956, Serial No. 41,514

Term of patent 14 years

(Cl. D50—3)

Fig. 1

Figure 1 is a front view of a pull showing my new design.

Fig. 2 is a sectional view taken along the line 2—2 of Fig. 1.

The design is characterized by the particular figure representation shown on the concave face of the knob.

I claim:

The ornamental design for a pull, substantially as shown and described.
